United States Patent Office

Des. 226,107

Patented Jan. 23, 1973

226,107

GOLF CLUB PUTTER

Frank John Indovina, 5266 Oak Park Ave.,
Encino, Calif. 91316

Filed June 14, 1971, Ser. No. 153,160

Term of patent 14 years

Int. Cl. D21—02

U.S. Cl. D34—5 GC

FIG. 1

FIG. 2

FIG. 3 FIG. 4

FIG. 5

FIG. 6

FIG. 1 is a front elevational view of a golf club putter showing my new design;

FIG. 2 is a rear elevational view thereof;

FIG. 3 is a side elevational view thereof;

FIG. 4 is a side elevational view showing the opposite side from that in FIG. 3;

FIG. 5 is a top end view thereof; and

FIG. 6 is a bottom end view thereof.

I claim:

The ornamental design for a golf club putter, substantially as shown.
